UNITED STATES PATENT OFFICE

166,603

TEAPOT OR SIMILAR ARTICLE

Sanford H. Hartman, Forest Hills, N. Y.

Application November 21, 1951, Serial No. 17,488

Term of patent 14 years

(Cl. D44—26)

To all whom it may concern:

Be it known that I, Sanford H. Hartman, a citizen of United States, residing at Forest Hills, New York city, in the county of Queens and State of New York, have invented a new, original, and ornamental Design for a Teapot or Similar Article, of which the following is a specification, reference being had to the accompanying drawing, forming part thereof.

In the drawing:

Fig. 1 is a front perspective view of a teapot showing my new design; and

Fig. 2 is a rear perspective view thereof.

I claim:

The ornamental design for a teapot or similar article, substantially as shown.

SANFORD H. HARTMAN.
